SUCTION NOZZLE FOR VACUUM
CLEANERS

Frederick Riebel, Jr., Toledo, Ohio, assignor to
Air-Way Electric Appliance Corporation, To-
ledo, Ohio, a corporation of Delaware

Original application September 9, 1929, Serial
No. 391,123. Divided and this application July
18, 1931. Serial No. 551,713

2 Claims. (Cl. 15—157)

The present invention relates as nominally indicated to vacuum cleaners, and pertains more particularly to the floor tools of such cleaners.

The present application is a divisional one of 5 my copending application Serial No. 391,123 filed September 9, 1929.

An object of this invention is to provide agitators for suction nozzles having an improvement in the design of the air passage groove 10 formed on the face thereof; and a further object of this invention is to provide a type of construction for such agitators which will provide a wearing surface of improved durability. Other objects and advantages will become apparent as the 15 description proceeds. To the accomplishment of the foregoing and related ends, said invention, then, consists of the means hereinafter fully described and particularly pointed out in the claims.

The annexed drawing and the following de- 20 scription set forth in detail certain mechanism embodying the invention, such disclosed means constituting, however, but one of various mechanical forms in which the principle of the invention may be used.

25 In said annexed drawing:

Fig. 1 is a combination elevation and sectional view of a suction nozzle embodying the principles of my invention; Fig. 2 is a section taken substantially on a plane indicated by the line 2—2 30 of Fig. 1; Fig. 3 is an enlarged fragmentary plan view of the suction nozzle agitators; and Fig. 4 is an enlarged section taken through the agitator element.

Referring more particularly to Fig. 1, the 35 suction nozzle 1 is provided with an opening 2 which is normally connected to the suction chamber of a vacuum cleaner (not shown). In marginal slots positioned in the lateral openings of the suction nozzle 1 are resiliently mounted 40 rollers 5 which may be adjusted as to their resilient position upon the floor by means of the movement of the cams 7. The wheel-carrying resilient tangs 3 and 4 are retained in lateral position by means of the retaining screws 6.

45 The agitator elements 10 are secured to the lower surface of the suction nozzle 1 by means of longitudinal slots 11 adjacent the suction slot 12 and the retaining screws 13 extend downwardly and inwardly of the retaining slot 11, border 50 said suction slot 12 on either side, and present wearing as well as thread-disturbing and agitating surface to the suction nozzle 1. The agitator elements 10 are usually made of a fibrous material and heretofore have been bent to conform 55 to the shape shown in Fig. 4. Being so bent, the

grain of such fibrous material would lie in a plane substantially parallel to the wearing surface of such agitator elements. With the grain in this position, agitator elements of this type were usually subject to excessive wear necessitating 60 their frequent replacement. These agitator elements 10 may be formed by cutting substantially rectangular blanks from a flat sheet and machining or otherwise forming them to the shape shown in Fig. 4. With the grain resting at an 65 angle to the surface, the amount of wear of such agitator elements 10 is considerably reduced due to the exceptional wearing properties of such fibrous material when the grain thereof runs at an angle to the wearing surface. 70

As shown in Fig. 3 and more especially in Fig. 4, the floor-contacting surfaces of such agitators is formed with a plurality of triangular shaped members 14, said members 14 being separated from each other by a plurality of grooves 15 associated 75 at their inner ends with the suction slot 12 and opening at their outer ends to provide a suction area over the surface to be cleaned. The improvement herein contemplated is to form such grooves 15 with an increased cross-sectional area 80 proportional to the distance away from said suction slot 12. This increased cross-sectional area is accomplished preferably by tapering the bottom 16 of the slots 15 substantially as shown in Figs. 2 and 4. The purpose of this improved 85 design is to more equally distribute the suction of the nozzle within said grooves 15, thereby materially increasing the efficiency of such suction nozzles.

The grooves 15 terminate so as to leave a com- 90 paratively short uncut surface 17 of said agitator elements 10 adjacent the ends of the suction slot 12, so as to materially increase the suction effect across the open end 18 of the suction nozzle, and also to strengthen the agitator elements 10 adjac- 95 ent the end-securing screws 13 and prevent such agitator element from splitting during installation or subsequent use.

It will thus be seen that my invention affords a 100 construction of the agitator elements which more efficiently accomplish the purpose for which they are intended.

Other modes of applying the principle of my invention may be employed instead of the one explained, change being made as regards the 105 mechanism herein disclosed, provided the means stated by any of the following claims or the equivalent of such stated means be employed.

I therefore particularly point out and distinctly 110 claim as my invention:

1. For attachment to a suction cleaner nozzle
 having a downwardly opening socket forming the
 lower extremity of a longitudinal wall, a lip agi-
 tator substantially L-shaped in cross section,
 5 including a vertical flange to be received in said
 socket and a horizontal flange the upper face
 of which forms an angle of substantially 90° with
 the adjacent face of said vertical flange, said
 horizontal flange being formed with grooves ex-
 10 tending from side to side thereof, opening down-
 wardly, and substantially completely bridged over
 by the upper region of said horizontal flange,
 said grooves defining downwardly projecting agi-
 tating projections bridged together for substan-
 15 tially their full width.
2. For attachment to a suction cleaner nozzle

having a downwardly opening socket forming the
 lower extremity of a longitudinal wall, a lip agi-
 tator substantially L-shaped in cross section, in-
 cluding a vertical flange to be received in said
 socket and a horizontal flange the upper face
 of which forms an angle of substantially 90° with
 the adjacent face of said vertical flange, and is at least as wide as the lower edge of the
 inner wall of said socket, said horizontal flange
 being formed with grooves extending from side
 to side thereof, opening downwardly, and sub-
 stantially completely bridged over by the upper
 region of said horizontal flange, said grooves de-
 fining agitating projections bridged together for
 substantially their full width.
